UNITED STATES PATENT OFFICE.

DON L. THOMPSON, OF SPOKANE, WASHINGTON.

BATH-CABINET.

1,065,853.

Specification of Letters Patent.

Patented June 24, 1913.

Application filed December 23, 1912. Serial No. 738,311.

To all whom it may concern:

Be it known that I, DON L. THOMPSON, a citizen of the United States, residing at Spokane, in the county of Spokane, State 5 of Washington, have invented certain new and useful Improvements in Bath-Cabinets; and I do hereby declare the following to be a full, clear, and exact description of the invention, such as will enable others skilled in 10 the art to which it appertains to make and use the same.

This invention is directed to improvements in bath cabinets, and has for its object to construct a cabinet whereby dry heat 15 or vapor may be utilized for the body.

With these and other objects in view, this invention resides in the novel features of construction, formations, combinations and arrangements of parts to be hereinafter 20 more fully described, claimed and illustrated in the accompanying drawings, in which:—

Figure 1 is a side elevation of the cabinet. Fig. 2 is a longitudinal sectional view. Fig. 3 is a sectional view on line 3—3 of Fig. 1. 25 Fig. 4 is an end view. Fig. 5 is a sectional view on line 5—5 of Fig. 1. Fig. 6 is a sectional view on line 6—6 of Fig. 1. Fig. 7 is a detail perspective view of the burner 30 supporting tube removed. Fig. 8 is a side elevation of the device showing the burners in the position when vapor is being employed for the bath.

Referring to the drawings, the numeral 1 designates the cabinet, which is formed 35 from sheet metal, and consists of end walls 2, side walls 3, and bottom 4, said bottom being semi-circular in cross section. The cabinet 1 is supported upon legs 5. The cabinet is preferably rectangular in shape, 40 and is of sufficient size to receive the body of the patient with comfort. Within the cabinet 1 is a body rest 6, which is composed of a plurality of longitudinally extending slats 7. One of the end walls 2 has an opening 8 formed therein to receive the neck of 45 the bather when lying upon the rest 6. Secured to the end wall 2 which is provided with the said opening 8 is a head rest 9, which may be adjusted at different inclinations 50 to suit the bather.

Mounted beneath the bottom of the cabinet is a tank 10, said tank having rising from its opposite ends pipe sections 11, said pipe sections being connected by a horizontal 55 steam pipe 12, which is provided with a plurality of alined perforations 13 in its under-

surface, so that when steam is generated in the tank 10 the same will be directed downwardly toward the bottom of the tank, thus not coming in direct contact with the body 60 of the bather. The pipe sections 11 may be secured in the bottom of the tank in any suitable manner so that the steam pipe 12 will be positioned within the cabinet so that steam therefrom will be directed to the body 65 of the patient.

Depending from one end of the tank 10 is a hanger 14, said hanger having a sleeve 15 formed at its lower end for slidably receiving the burner supporting tube 15'. Detachably connected to the tube 15' are burners 16, which may be of any conventional form. A hanger 17 is provided, and depends from the other end of the tank 10, 70 said hanger being substantially V-shaped, 75 and is provided near its lower end with a pair of spaced lugs 18, which slidably engage the sides of the web 19 mounted upon one end of the burner supporting tube 15', thus preventing rotation of said tube when 80 supported in the hangers, but at the same time allowing the same to be slidably adjusted.

Extending through the tank 10, and near the outer ends thereof, are flues 20, so that 85 when the burners are in the position as shown in Fig. 1 heat therefrom will be directed through said flues and directly upon the bottom of the cabinet.

To generate steam within the tank 10 90 it is only necessary to slide the burner supporting tube in a position as shown in Fig. 8, whereupon the flame from the burners will be directed directly against the bottom of the tank 10, thus generating steam 95 therein which passes through the pipe 12 and out of the perforations 13 formed therein.

To prevent over filling of the tank 10 100 an indicator 21 is provided and is connected to the tank 10 by a pipe 22, said indicator comprising a vertical tube 23, having operable therein a float operated indicating rod 24.

Connected to the lower end of the indicator tube 21 is a drain cock 25, the same being operable to drain the water from the tank 10 when desired.

From this construction it will be seen that 110 when the bather desires to be treated with vapor, the burners are positioned as shown in Fig. 8, thereby heating the water in the

tank 10 to generate steam, and if it is desired to be treated with heat alone the burner tube is shifted to the position as shown in Fig. 1, whereby the heat is directed to the bottom of the cabinet.

What is claimed is:—

1. A bath cabinet comprising sides, end walls and a bottom, a water tank supported below the bottom, a steam pipe located 10 within the cabinet and having connection with the steam tank, flues formed in said tank, a burner supporting tube slidably mounted beneath the tank, said tube being slidably adjusted so that the burners carried thereby may be shifted under the flues.
- 15 2. A bath cabinet comprising sides, end walls, and a bottom, a body rest supported in the cabinet, a steam tank mounted below the bottom and connected to a steam pipe

located within the cabinet, flues formed in 20 the steam tank, hangers extending from the opposite ends of the steam tank, one of said hangers having spaced lugs carried thereby, a burner supporting tube slidably mounted in the hangers, one end of said tube being 25 provided with a web for slidably engaging the lugs of the hanger to prevent accidental rotation of the burner supporting tube, said burner supporting tube being adapted to be shifted so that the burners carried thereby 30 may be positioned under the flues of the water tank or bottom of said tank.

In testimony whereof, I affix my signature, in presence of two witnesses.

DON L. THOMPSON.
